CLAIM

The ornamental design for a light fixture, as shown and described.

DESCRIPTION

FIG. 1 is a bottom perspective view of an embodiment of a light fixture.

FIG. 2 is a bottom plan view of the light fixture of FIG. 1.

FIG. 3 is a top plan view of the light fixture of FIG. 1.

FIG. 4 is a right side elevation view of the light fixture of FIG. 1.

FIG. 5 is a left side elevation view of the light fixture of FIG. 1.

FIG. 6 is a front elevation view of the light fixture of FIG. 1.

FIG. 7 is a rear elevation view of the light fixture of FIG. 1.

FIG. 8 is a cross-sectional view of the light fixture taken along line 8-8 of FIG. 2.

FIG. 9 is an enlarged isolated view of a reflector of the light fixture of FIG. 8.

FIG. 10 is a bottom perspective view of another embodiment of a light fixture.

FIG. 11 is a bottom plan view of the light fixture of FIG. 10.
FIG. 12 is a top plan view of the light fixture of FIG. 10.
FIG. 13 is a right side elevation view of the light fixture of FIG. 10.
FIG. 14 is a left side elevation view of the light fixture of FIG. 10.
FIG. 15 is a front elevation view of the light fixture of FIG. 10.
FIG. 16 is a rear elevation view of the light fixture of FIG. 10.
FIG. 17 is a cross-sectional view of the light fixture taken along line 17-17 of FIG. 11.
FIG. 18 is an enlarged isolated view of a reflector of the light fixture of FIG. 17.
FIG. 19 is a bottom perspective view of another embodiment of a light fixture.
FIG. 20 is a bottom plan view of the light fixture of FIG. 19.
FIG. 21 is a top plan view of the light fixture of FIG. 19.
FIG. 22 is a right side elevation view of the light fixture of FIG. 19.
FIG. 23 is a left side elevation view of the light fixture of FIG. 19.
FIG. 24 is a front elevation view of the light fixture of FIG. 19.
FIG. 25 is a rear elevation view of the light fixture of FIG. 19.
FIG. 26 is a cross-sectional view of the light fixture taken along line 26-26 of FIG. 20.

FIG. 27 is an enlarged isolated cross-sectional view of a reflector of the light fixture of FIG. 26.
FIG. 28 is an enlarged isolated cross-sectional view of a louver blade taken along line 28-28 of FIG. 26.
FIG. 29 is a bottom perspective view of another embodiment of a light fixture.
FIG. 30 is a bottom plan view of the light fixture of FIG. 29.
FIG. 31 is a top plan view of the light fixture of FIG. 29.
FIG. 32 is a right side elevation view of the light fixture of FIG. 29.
FIG. 33 is a left side elevation view of the light fixture of FIG. 29.
FIG. 34 is a front elevation view of the light fixture of FIG. 29.
FIG. 35 is a rear elevation view of the light fixture of FIG. 29.
FIG. 36 is a cross-sectional view of the light fixture taken along line 38-38 of FIG. 30.
FIG. 37 is an enlarged isolated cross-sectional view of a reflector of the light fixture of FIG. 36; and,
FIG. 38 is an enlarged isolated cross-sectional view of a louver blade taken along line 38-38 of FIG. 36.
Portions or features of the light fixture not shown in the drawings form no part of the claimed design. The broken lines in the drawings illustrating portions of the lighting fixture form no part of the claimed design.
